CLAIM

The ornamental design for a positive airway pressure delivery console, as shown and described.

DESCRIPTION

FIG. 1 is a perspective view, from the front, right corner, of a positive airway pressure delivery console according to our new design;

FIG. 2 is a front view thereof;

FIG. 3 is a rear view thereof;

FIG. 4 is a top view thereof;

FIG. 5 is a bottom view thereof;

FIG. 6 is a right side view thereof; and

FIG. 7 is a left side view thereof;

FIG. 8 is a perspective view, from the front, right corner, of a positive airway pressure delivery console according to our new design;

FIG. 9 is a front view thereof;

FIG. 10 is a rear view thereof;

FIG. 11 is a top view thereof;

FIG. 12 is a bottom view thereof;

FIG. 13 is a right side view thereof; and,

FIG. 14 is a left side view thereof.

1 Claim, 12 Drawing Sheets
